(57) **CLAIM**

The ornamental design for a bracket with latch for coupling a global positioning system related device to a pole, as shown.

DESCRIPTION

FIG. 1 is an upper left front perspective view of the bracket with latch for coupling a global positioning system related device to a pole comprising the present invention in the open condition;

FIG. 2 is a lower right rear perspective view thereof in the open condition;

FIG. 3 is a front elevational view thereof in the open condition;

FIG. 4 is a right side elevational view thereof in the open condition;

FIG. 5 is a rear elevational view thereof in the open condition;

FIG. 6 is a left side elevational view thereof in the open condition;

FIG. 7 is a top plan view thereof in the open condition;

FIG. 8 is a bottom plan view thereof in the open condition;

FIG. 9 is an upper left front perspective view thereof in the closed condition;

FIG. 10 is a lower right rear perspective view thereof in the closed condition;

FIG. 11 is a front elevational view thereof in the closed condition;

FIG. 12 is a right side elevational view thereof in the closed condition;

FIG. 13 is a rear elevational view thereof in the closed condition;

FIG. 14 is a left side elevational view thereof in the closed condition;

FIG. 15 is a top plan view thereof in the closed condition; and,

FIG. 16 is a bottom plan view thereof in the closed condition.
